PROCESS FOR PREPARING HIGH
ANTIKNOCK GASOLINEOgden Fitz Simons, Hammond, Ind., assignor to
Standard Oil Company, Chicago, Ill., a corpora-
tion of Indiana

Application May 22, 1933, Serial No. 672,122

8 Claims. (Cl. 196—37)

This invention relates to the preparation of high antiknock gasoline from gasolines of relatively low knock ratings and it pertains more particularly to improvements in the sulfur dioxide extraction process for producing high antiknock motor fuels.

It has long been known that certain solvents, such as sulfur dioxide, have the property of extracting naphthenic from paraffinic hydrocarbons ranging from gasoline to wax. In these processes the first extract is most naphthenic in nature and the raffinate is paraffinic. If the raffinate is re-extracted it may be separated into a component which is more paraffinic than the first raffinate and another component which is less paraffinic than the first raffinate but more paraffinic than the first extract. In other words, by repeated extractions it has been possible to separate an oil into several fractions of gradually increasing paraffinicity.

The present invention is not primarily concerned with the separation of paraffinic from naphthenic components of a petroleum oil—it is specific to the gasoline fraction and it is concerned with the separation of high antiknock components from low antiknock components. In other words, the object of my invention is to prepare a high grade motor fuel from a low grade motor fuel, whether the low grade fuel is of petroleum origin or whether it comes from shale oil, the destructive distillation of carbonaceous materials, the distillation of petroleum, or the cracking, polymerization or hydrogenation of petroleum or carbonaceous products. More specifically, the object of my invention is to fractionate a motor fuel into components of different knock ratings or octane numbers and to obtain maximum yields of motor fuels having extremely high octane numbers.

A further object of my invention is to adapt a sulfur dioxide extraction for use with motor fuels so that the yields of high antiknock gasoline will be increased and so that gasoline of higher octane number will be produced than have hitherto been produced by sulfur dioxide extraction (see U. S. 1,585,473 and 1,661,566). A further object is to provide a complete process for the preparation of high grade motor fuels, including stabilization and finishing treatments as well as fractionation of solvents. Other objects will be apparent as the detailed description of my invention proceeds.

I have discovered that when a motor fuel is extracted with sulfur dioxide it is highly desirable to operate at extremely low temperatures, much

lower than any temperatures heretofore used in solvent extraction processes. I have also discovered that there is a critical range in which products of maximum octane number are obtainable. The first extracts have a considerably lower octane number than the extracts in this critical range, and the extracts beyond this range likewise have a lower octane number. Starting with a gasoline having an octane number of 62 and using amounts of sulfur dioxide necessary to obtain varying amounts of extracts at 5° F. I have found that a 10% extract has an octane number of about 68, a 30% extract about 80, a 50% extract of about 79 and a 70% extract of about 72 octane number. Operating in this manner it is impossible to obtain an octane number higher than 81. However, if the first 10% extract is discarded and a sufficient amount of sulfur dioxide is added to effect the separation of the next 30% (based on original gasoline) I have discovered that much higher octane numbers may be obtained.

I have also discovered that when the fractionation is effected at a temperature of —90° F. the first 10% fraction will have an octane number of about 86; the first 30% fraction of about 97, the first 50% fraction of about 89, and the first 70% fraction of about 76 octane number. In this case it will be observed that with the same yields of extracts I obtain very much higher antiknock ratings. A 30% extract at 50° F. had a knock rating of only 80 while a 30% extract at —90 had an octane rating of 97. Now if the first fraction is discarded in the low temperature extraction process I have discovered that motor fuels may be obtained with a knock rating ranging from 100-110 octane number,—a result which is heretofore unprecedented.

The invention will be more clearly understood by reference to the accompanying drawings which form a part of this specification and in which—

Figure 1 is a diagrammatic plan of my improved system, and

Figure 2 is a graph showing the effect of different extraction temperatures and the use of amounts of sulfur dioxide to produce different amounts of extracts.

Sulfur dioxide from storage tank 10 is introduced by pipe 11 through pump 12 and pipe 13 to mixer 14. The gasoline or motor fuel to be treated is introduced from any suitable storage tank through pipe 15 and heat exchanger 16, where it is cooled, into said mixer, the combined mixture being introduced into cooler 17. This cooler may be provided with cooling coils for the circulation of brine or it may be jacketed so

that cooling may be effected by the vaporization of carbon dioxide, ethane, propane, etc. from an external jacket. In the preferred embodiment, however, the refrigeration is effected by 5 vaporizing a part of the sulfur dioxide, the sulfur dioxide vapors being withdrawn through pipe 18 by compressor 19 and forced through heat exchanger 20 or other suitable condensers or coolers back to storage tank 10. It will be understood that instead of using a single compressor 10 I may compress the vapors in stages and I may maintain the temperature of the storage tank 10 at any desired point by removing vapors from the upper part thereof, condensing them and 15 reintroducing the condensed vapors into the storage tank.

The cooled mixture of sulfur dioxide and gasoline, which may be at 0° F., is introduced by pipe 21 into separator 22, the extract being withdrawn 20 through pipe 23 to a suitable stabilizing or stripping tower and the raffinate being transferred by pipe 24 to the base of countercurrent extractor 25.

Sulfur dioxide from storage tank 10, pipe 11 and pump 12 is introduced by pipe 26 into cooler 27, which may consist of a heat exchange device or of a suitable tank from which vapors may be withdrawn through pipe 28 by compressor 29 and returned through heat exchanger 30 through 30 pipe 31. The cooled sulfur dioxide is then introduced by pipe 32, pump 33 and pipe 34 to the upper part of the countercurrent extractor 25. Extract from the base of the extractor is withdrawn through pipe 35 to a suitable stabilizing 35 tower and the raffinate is withdrawn through pipe 36, heat exchanger 37 and heat exchanger 38 to stabilizing tower 39. Tower 39 is equipped with a steam coil 40 at the base thereof with suitable fractionating and/or stripping plates 41. Vapors leave the top of this tower through pipe 42 and reflux is introduced at the top through pipe 43. The stabilized raffinate is withdrawn from the base of the tower through pipe 44, heat exchanger 38 and pipe 45.

45 The extract from extractor 25 passes through pipe 35, heat exchanger 46 and heat exchanger 47 to stabilizer tower 48, which contains steam coil 49, fractionating and/or stripping plates 50, vapor outlet 51 and reflux supply 52. The stabilized and/or stripped gasoline (extract) is withdrawn 50 from the base of the tower through pipe 53 and it is passed through heat exchanger 47 and pipe 54 to a suitable storage tank.

The extract from separator 22 is passed through 55 pipe 23, heat exchanger 55 and heat exchanger 56 to stabilizer 57. This stabilizer is provided with heater coil 58, fractionating and/or stripping plates 59, vapor outlet 60 and reflux supply 61. The stabilized and stripped gasoline is withdrawn 60 through pipe 62 and passed through heat exchanger 56 and pipe 63 to a suitable storage tank.

Vapor conduits 42, 51 and 60 lead to vapor main 64, which leads to condenser 65 and collector 66. Gases are withdrawn from the top of this collector through pipe 67 and liquids are moved through pipe 68. This liquid may either be withdrawn through pipe 69 to a suitable storage tank and/or it may be circulated through 70 pump 70 and reflux line 71 to supply reflux to the strippers through pipes 61, 52 and 43. Gases from 67 are returned to storage drum 10 after compression and condensation—they may be introduced into pipe 18.

75 For the sake of simplicity many of the heat

exchange systems have not been shown in detail. For instance, heat exchangers 46 and 55 may take the place of heat exchanger 16 in the incoming gasoline line or, as shown by the drawings, wherein pipe 15 is brought in heat exchange relation with pipes 23 and 35 and wherein pipes 23 and 35 are operated in heat exchange relation with pipe 15. Likewise, pipe 36 may be in heat exchanged relation to pipe 31 or 15. Other heat exchange systems along these general lines may be employed. 5

The operation of my invention may be understood from a specific embodiment wherein a high grade motor fuel is prepared from cracked heavy naphtha having an initial of 275° F., a maximum of 430° F. and an octane number of 62. In determining the octane numbers on resulting products, these products were redistilled to 400 end point. 15

The invention will first be described at an 20 operating temperature of 5° F. The exact amount of sulfur dioxide mixed with the incoming naphtha will depend to a large extent on the design of heat exchange equipment and the insulation of the system, but sufficient sulfur dioxide should be added so that it will leave 55% by volume based on the incoming naphtha. When the mixture leaving cooler 17 is slightly below 5° F., about 5-10% of the naphtha charged 25 will be withdrawn as extract in the sulfur dioxide layer through pipe 23, this extract is simultaneously stabilized and stripped of sulfur dioxide 30 in stabilizer tower 57 and it yields a motor fuel having an octane number of about 68. 35

The raffinate from pipe 24 is extracted with 35 an additional amount of sulfur dioxide, which is preferably about 100-150% by volume of the naphtha originally charged. The amount of sulfur dioxide in this case is not critical and it should be regulated to give an extract of about 40 30-50% of the volume of naphtha charged. This will yield a finished extract having an octane number of about 85 while the highest possible octane number obtainable in a one-step extraction process would be about 81. By discarding 45 the first fraction extracted I obtain a gasoline of higher knock rating than would otherwise be possible and at the same time I increase the yield of this high grade gasoline. 50

In my preferred embodiment I operate at extremely low temperature, preferably -90° F. 55 In this case, considerably more sulfur dioxide will have to be mixed with the incoming naphtha in order that the temperature of the mixture leaving the cooler through pipe 21 shall be at this low temperature and at the same time retain enough sulfur dioxide to give an extract of about 5% or 10% of the volume of the naphtha charged. This fraction will have an octane number of about 86 and is comparable to the best motor fuel obtainable at the higher temperature. I prefer, 60 however, to remove this fraction and re-extract the raffinate in extractor 25 with a sufficient amount of sulfur dioxide, which has been cooled in flash chamber 27 to -90° F., to produce an extract of about 25-35% by volume of the naphtha charged. In this case the octane number of the second extract will be about 103 while the highest possible octane number that could be obtained in a one step process would be 70 about 96. Furthermore, the yield of this high quality gasoline is about 30% of the volume of naphtha charged and a 40% yield with a single extraction step would only have an octane number of about 93. 75

The invention will be more clearly understood by reference to the graphs in Figure 2, showing the results of extracting 62 octane heavy naphtha at +5° F. In these graphs one line represents the yield and octane number obtainable in single extractions with varying quantities of sulphur dioxide to produce varying percentages of extract. The other line indicates the variation in yield and octane number of separate increments of gasoline which would be obtained by successive extraction of small increments, and is in fact a differential curve. It will be seen that the peak in the differential graph lies between extract percentages of about 10 and 40% yield, giving a 30% yield of gasoline with an average octane number well above 75. In practicing my invention I segregate the components of the gasoline falling within the peak on the differential curves from the fractions which precede and follow said peak, and I thereby obtain higher quality gasoline with larger yields than could otherwise be obtained.

Instead of increasing the amount of sulphur dioxide for the second extraction process and re-extracting the raffinate I may first use enough sulphur dioxide to obtain an extract of about 50% of the gasoline charged, and I may then remove enough of the sulphur dioxide from the extract phase to cause about 30% or 40% thereof to separate out as raffinate and to leave about 5% to 10% as a second extract. If the process is carried out in this way the second raffinate will have the extremely high antiknock value and the second extract will be a gasoline of intermediate knock rating.

Also, it has been found that if the extraction is carried out in the presence of a hydrocarbon more volatile than gasoline, particularly ethane, propane or butane, higher knock ratings can be produced than can possibly be produced by extraction with sulphur dioxide alone at the same temperatures, even when a single extraction step is used. For instance, when one volume of propane, one volume of naphtha and two volumes of sulphur dioxide are intimately mixed and then separated at a temperature of about -90° F., an extract is obtained which contains a considerable amount of propane, and when this extract is stabilized it is found to have knock ratings of 110-115. It has also been found that carbon dioxide admixed with sulphur dioxide makes it possible to obtain gasolines of higher knock ratings than could possibly be obtained by sulphur dioxide alone at any given temperature. The separation and segregation of a series of fractions of varying knock rating in the manner described herein is applicable to any of these solvents and solvent mixtures, as well as with other selective solvents.

The low antiknock raffinate from any of the above processes is not suitable for use as a motor fuel in internal combustion engines of modern design and therefore it should preferably be cracked or "re-formed" so that by this thermal or pyrolytic process it may be converted into a high antiknock product. The re-formed heavy naphtha may be returned to the extraction process.

The extracts obtained in my system may require further treatment to remove the last traces of sulphur dioxide and to render them stable against oxidation, discolorization, gum formation, etc. These gasolines may be refined with a light sulfuric acid treatment, for example, with 75% acid, and they may be neutralized

with alkali, sweetened with doctor or hypochlorite, or treated with clay in the vapor phase either before or after the extraction process. Also, the gasoline may be stabilized by the addition of inhibitors, antioxidants or other dopes which are commonly used to prevent deterioration of high antiknock motor fuels.

While I have described in detail a preferred embodiment of my invention it should be understood that I do not limit myself to any of the details hereinabove set forth except as defined by the following claims which should be construed as broadly as the prior art will permit. For instance, the equipment for stripping the sulphur dioxide out of the various fractions will probably consist of at least two stages, first under a pressure sufficiently high so that cooling water will condense the sulphur dioxide and then at very low pressures at high temperatures for complete sulphur dioxide removal. From the latter stage the sulphur dioxide will have to be compressed, and it will therefore be introduced into one of the stages of the multistage compressor hereinabove referred to. Such expedients are familiar to those skilled in the art and they are therefore not described in detail.

I claim:

1. The method of separating a motor fuel into components of higher and lower knock ratings than the original motor fuel, which comprises extracting said motor fuel with sulphur dioxide at a low temperature to obtain an extract of about 5% to 10% based on the volume of motor fuel charged, separating said extract from the raffinate, extracting the raffinate with sufficient sulphur dioxide to produce an extract of about 20% to 50% of the motor fuel charged, separating said extract from the remaining components of the motor fuel, and removing sulphur dioxide from said second extract to produce a motor fuel of maximum knock rating.

2. The method of separating a motor fuel into components of higher and lower knock ratings, than the original motor fuel which comprises admixing said motor fuel with liquefied sulphur dioxide, cooling said mixture to a temperature not higher than about 5° F., regulating the proportions of sulphur dioxide to motor fuel so that the cooled mixture will contain 55% sulphur dioxide by volume based on the motor fuel, separating the cooled mixture as a raffinate and an extract, adding about 100-150% by volume (based on motor fuel originally charged) of liquid sulphur dioxide to said raffinate, separating about 30% to 50% of the volume of motor fuel charged as extract in the added sulphur dioxide, and removing the sulphur dioxide from the extract to yield motor fuel of high anti-knock rating.

3. The process of claim 2 wherein the cooling is obtained by vaporizing a normally gaseous refrigerant in the mixture with said motor fuel.

4. The method of obtaining a high antiknock motor fuel from cracked naphtha, which comprises adding a normally gaseous diluent to said naphtha and refrigerating said naphtha at very low temperature by vaporization of said diluent, extracting said cooled naphtha at a very low temperature with enough sulfur dioxide to give an extract of about 5% to 10% by volume of the naphtha charged, separating said extract from the raffinate, re-extracting said raffinate with a sufficient amount of sulfur dioxide to produce an extract of about 25% to 35% by volume of the naphtha charged, separating said extract from 75

- the said raffinate and separating the sulfur dioxide from the extract, finishing the extract to produce a high quality gasoline of high antiknock rating.
5. The method of obtaining a high antiknock motor fuel from cracked naphtha, which comprises adding a normally gaseous diluent to said naphtha and refrigerating said naphtha at very low temperature by vaporization of said diluent, extracting said cooled naphtha at a very low temperature with enough sulfur dioxide to give an extract of about 5 to 10% by volume of the naphtha charged, separating the extract from the raffinate, re-extracting said raffinate counter-currently with a sufficient amount of sulfur dioxide to produce an extract of about 25% to 30% by volume of the naphtha charged, again separating said extract from said raffinate and separating the sulfur dioxide from the extract and finishing the extract to produce a high quality gasoline of high antiknock rating.
6. The method of separating a motor fuel in components of higher and lower antiknock ratings than the original motor fuel, which comprises extracting said motor fuel with liquid sulfur dioxide at a temperature not higher than about 5° F. to obtain an extract of about 5 to 10% based on the volume of the motor fuel charged, separating said extract from the raffinate, again extracting the raffinate with sufficient sulfur dioxide at a temperature of about -70° F. to 0° F. to produce an extract of about 20 to 50% of the motor fuel, separating said extract from the remaining components and removing sulfur dioxide from the second extract to produce a motor fuel of maximum antiknock rating.
7. The method of obtaining a high antiknock motor fuel from cracked naphtha, comprising adding a normally gaseous diluent having a volatility below that of the naphtha to said naphtha and refrigerating said naphtha at a very low temperature by vaporizing a part of said diluent, extracting said cool naphtha at a temperature below about 5° F. with enough sulfur dioxide to give an extract of about 5 to 10% by volume of the naphtha charged, separating said extract from the raffinate, re-extracting said raffinate with a sufficient amount of sulfur dioxide to produce an extract of about 25 to 35% by volume of the naphtha charged, separating said extract from the said raffinate and separating the sulfur dioxide from the extract and finishing the extract to produce a high quality gasoline of high antiknock rating.
8. The method of separating cracked naphtha into components of higher and lower antiknock ratings than the original cracked naphtha, which comprises extracting said naphtha at a very low temperature with enough sulfur dioxide to give an extract of about 5 to 10% by volume of the naphtha charged, separating the extract from the raffinate, re-extracting said raffinate with another portion of liquid sulfur dioxide at a temperature of about -90° F. to 0° F. to produce an extract of about 25 to 35% by volume of the naphtha charged, separating the sulfur dioxide from this extract and raffinate and finishing the extract to produce a high quality gasoline of high antiknock rating.

- the said raffinate and separating the sulfur dioxide from the extract, finishing the extract to produce a high quality gasoline of high antiknock rating.
5. The method of obtaining a high antiknock motor fuel from cracked naphtha, which comprises adding a normally gaseous diluent to said naphtha and refrigerating said naphtha at very low temperature by vaporization of said diluent, extracting said cooled naphtha at a very low temperature with enough sulfur dioxide to give an extract of about 5 to 10% by volume of the naphtha charged, separating the extract from the raffinate, re-extracting said raffinate counter-currently with a sufficient amount of sulfur dioxide to produce an extract of about 25% to 30% by volume of the naphtha charged, again separating said extract from said raffinate and separating the sulfur dioxide from the extract and finishing the extract to produce a high quality gasoline of high antiknock rating.
6. The method of separating a motor fuel in components of higher and lower antiknock ratings than the original motor fuel, which comprises extracting said motor fuel with liquid sulfur dioxide at a temperature not higher than about 5° F. to obtain an extract of about 5 to 10% based on the volume of the motor fuel charged, separating said extract from the raffinate, again extracting the raffinate with sufficient sulfur dioxide at a temperature of about -70° F. to 0° F. to produce an extract of about 20 to 50% of the motor fuel, separating said extract from the remaining components and removing sulfur dioxide from the second extract to produce a motor fuel of maximum antiknock rating.
7. The method of obtaining a high antiknock motor fuel from cracked naphtha, comprising adding a normally gaseous diluent having a volatility below that of the naphtha to said naphtha and refrigerating said naphtha at a very low temperature by vaporizing a part of said diluent, extracting said cool naphtha at a temperature below about 5° F. with enough sulfur dioxide to give an extract of about 5 to 10% by volume of the naphtha charged, separating said extract from the raffinate, re-extracting said raffinate with a sufficient amount of sulfur dioxide to produce an extract of about 25 to 35% by volume of the naphtha charged, separating said extract from the said raffinate and separating the sulfur dioxide from the extract and finishing the extract to produce a high quality gasoline of high antiknock rating.
8. The method of separating cracked naphtha into components of higher and lower antiknock ratings than the original cracked naphtha, which comprises extracting said naphtha at a very low temperature with enough sulfur dioxide to give an extract of about 5 to 10% by volume of the naphtha charged, separating the extract from the raffinate, re-extracting said raffinate with another portion of liquid sulfur dioxide at a temperature of about -90° F. to 0° F. to produce an extract of about 25 to 35% by volume of the naphtha charged, separating the sulfur dioxide from this extract and raffinate and finishing the extract to produce a high quality gasoline of high antiknock rating.
